(57) **CLAIM**

The ornamental design for a set of bristles for an electric toothbrush, as shown and described.

DESCRIPTION

FIG. 1 is a perspective view of a set of bristles for an electric toothbrush.

FIG. 2 is a front view of the set of bristles for an electric toothbrush.

FIG. 3 is a rear view of the set of bristles for an electric toothbrush.

FIG. 4 is a side view of the set of bristles for an electric toothbrush, the opposite side being a mirror image thereof.

FIG. 5 is a top view of the set of bristles for an electric toothbrush.

FIG. 6 is a bottom view of the set of bristles for an electric toothbrush; and,

FIG. 7 is an enlarged perspective view of the set of bristles for an electric toothbrush illustrated in FIG. 1.

The parts shown in dashed lines in FIGS. 1-7 are shown for illustrative purposes only and form no part of the claimed design.
